ARCHITECTURAL PANEL

Marvin H. Williams, New Kensington, Pa., assignor to Aluminum Company of America, Pittsburgh, Pa.

Filed Apr. 5, 1972, Ser. No. 241,493

Term of patent 14 years

Int. Cl. D25—01

U.S. Cl. D54—2 A

FIG. 1 is a top plan view of said architectural panel exhibiting an angular exterior surface, a portion of a similar adjacent panel being shown in dotted lines at one edge thereof;

FIG. 2 is a broken, front elevation view of the design illustrated in FIG. 1.

The broken line showing is for illustrative purposes only. FIG. 2 is broken to show indeterminate length.

I claim:

The ornamental design for an architectural panel, substantially as shown and described.
